FIG. 1 is a perspective view of the angle driver;

FIG. 2 is a side view thereof;

FIG. 3 is an opposing side view thereof;

FIG. 4 is a top view thereof;

FIG. 5 is a bottom view thereof;

FIG. 6 is a front view thereof; and,

FIG. 7 is a rear view thereof.

The broken lines shown in the drawings illustrate portions of the angle driver that forms no part of claimed design.
